CLAIM

The ornamental design for a display screen with animated graphical user interface for card squeezing, as shown and described.

DESCRIPTION

FIG. 1 is a front view of a display screen with animated graphical user interface for card squeezing showing a first image of the claimed design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the animated image sequentially transitions between the images shown in FIGS. 1-6.

The process or period in which one image transitions to another forms no part of the claimed design.

The broken lines in the figures show a display screen and portions of the animated graphical user interface that form no part of the claimed design.
